UNITED STATES PATENT OFFICE

1,991,660

CONTROL OF FANS, BLOWERS, AND PUMPS

Thomas Bosanko Collins, Glasgow, Scotland

Application June 14, 1933, Serial No. 675,832

In Great Britain July 14, 1932

2 Claims. (CL 230—114)

This invention relates to improved means of controlling the volumetric output and discharge pressure of fans, blowers, pumps and the like of the centrifugal or propeller type, by varying the intake, being more particularly applicable to units driven at a constant speed. Another form of this invention is the subject matter of applicant's copending application, Serial No. 675,499, filed June 12, 1933.

10 The improved controlling means according to the present invention are of the kind in which a deflector provided in an entrance chamber to the casing, from which the fluid enters the eye of the fan, is adapted to be adjusted to vary the throat of the entrance chamber in such a manner that the delivery of the fluid into the said casing shall be in a direction tangential to circles concentric with the axis of rotation of the impeller, or propeller.

20 According to the present invention, use is made of an intake of rectangular cross-section, terminating in a substantially half-cylindrical wall surrounding the eye of the fan casing or the like at the farther end of the intake, and the controlling means comprise two movable hinged plates provided in the said intake, of which one plate is adapted to be moved along the said half-cylindrical wall at the farther end of the intake and be brought around the remainder of the eye of the fan casing or the like, thereby closing more or less the throat of the intake while the other plate, which may be flat, curved, or partly flat and partly curved, is adapted to be displaced during the said movement within the intake and form a nozzle of smaller or greater convergence.

30 The invention also consists in the particular constructions of hinged plates and means for operating them.

40 Another feature of the invention consists in the provision of one or more adjustable deflectors in the intake.

The invention also consists in the improved constructions of fans, blowers, pumps and the like provided with controlling means of the kind referred to as hereinafter more particularly described.

Referring to the accompanying drawings, which illustrate the invention by way of example,

50 Figs. 1 and 2 are respectively a sectional elevation and a cross-section of a single inlet fan.

Figs. 3 and 4 are similar views of a modified form of construction applied to a double inlet fan of which only one side is shown.

55 Figs. 5 and 6 are similar views of a further

modification embodied in a single inlet pump and

Figs. 7 and 8 are respectively a sectional elevation and a plan view, partly in section, of a still further modification applied to a double inlet pump.

Referring to the construction of single inlet fan illustrated in Figures 1 and 2, *a* is an entrance chamber or intake channel of rectangular cross-section, terminating in a substantially half-cylindrical wall *b* which is preferably concentric with the eye *c* provided in the fan casing *d* and with the axis of the impeller provided in the casing *d*. The longitudinal axis of the intake channel *a* is at right angles to the axis of rotation of the impeller and thus parallel to the plane of the impeller disc.

The means for controlling the inflow mainly consists of two hinged portions, the one comprising, in this instance, a flat rectangular plate *e* and the other one a number of short plates *f* linked together and forming a substantially cylindrical wall in continuation of the wall *b* and concentric with the axis of the impeller. The width of the hinged portions *e* and *f* is equal to the width of the intake channel *a* measured at right angles to the plane of the disc of the impeller, the free end *e'* of the plate *e* being provided at the sides with rollers *e*² guided along rails *g* attached to the inner side walls of the intake channel, and the free end *f'* of the portion formed by the linked plates *f* being moved in contact with the cylindrical wall *b*, the sides of the plates *f* being guided by rollers *f*² along circular guiding rails *h* attached to the fan casing *a* and the inner wall of the intake channel *a* opposite one another.

Instead of guiding the movable plates *e* and *f* by rollers, use may be made of sliding shoes, and instead of guiding the interlinked plates *f* along a cylindrical path, they may be caused to follow an involute to the cylindrical portion *b* of the intake channel.

The means for controlling the movable plates may consist of a screw-threaded rod *i* pivotally attached to the plate *e*, and operated by a hand-wheel *j*. As can be seen from the drawings, the plate *e* forms a convergent nozzle with three of the walls of the intake channel, and the inter-linked plates *f* on a substantially cylindrical inlet casing facing the eye of the fan and communicating with the said converging nozzle by a throat, the size of which is varied by the displacement of the plates. It will also be seen that by this construction the fluid stream flows tan-

gentially to a circle concentric with the axis of the impeller and is constrained to keep this path by the cylindrical chamber at the eye of the fan, and this circumferential flow may be either in or against the direction of rotation of the impeller.

In order to minimize eddies, one or more preferably stream-lined deflectors *k* are pivoted within the intake channel *a*, with their axes parallel to the axis of the impeller, the said deflectors being capable of being adjusted by means provided outside the intake channel, for instance, counter-weights *l*. The deflectors may be adapted to be operated separately or simultaneously and be fixed in the adjusted positions.

When the intake channel *a* operates at maximum opening, the plate *e* lies along the lowest side of the channel, shown in the drawings, while the portion of interlinked plates *f* lies along and within the curved wall *b*, the separate deflectors *k* being then so placed as to ensure a stream-line flow to the eye of the impeller.

m is a hinged plate which rests against the plate *e* automatically following its up and down displacement and covering its end part irrespective of the position assumed by the said plate *e* within the intake channel.

In the modification of double inlet fan illustrated in Figures 3 and 4, the movable plate *e* is hinged to a half-cylindrical plate *f* preferably having a straight end portion *f'* intended to move along the wall *b* of the intake channel *a*. The operation is effected by means of a toothed segment *n* attached to the half-cylindrical plate *f* and engaging with a pinion *o* operated from the outside by a hand-wheel *p*.

In the modification of single inlet pump illustrated in Figures 5 and 6, the half-cylindrical plate *f* hinged to the flat plate *e* is attached to a sectorial frame *q* which can be operated by an external handle *r*, the axis of which coincides with the axis of the impeller.

In the modification of double inlet pump illustrated in Figures 7 and 8, an intake channel *a* is associated with an inlet casing on both sides of the pump casing *d* and the half-cylindrical

plate *f* is shown as being operated by a toothed segment *n* and pinion *o*, as in the construction of fan shown in Figures 3 and 4, but the plate *e* is curved, instead of being flat. The two pinions *o* associated with the respective toothed segments *n* are mounted on short stub shafts *s*, which are turned from a common spindle *u* by means of a hand-wheel *t*, through the intermediary of well-known bevel gear transmission, it being understood that the said hand-wheel may be replaced by an electric motor which may be controlled from a distance.

The invention hereinbefore described may also be applied to constructions of fans, pumps, or the like, in which one central intake is provided between two impeller casings and I wish it to be understood that the various details may be modified without in any way departing from the scope of the invention as claimed in the appended claims.

What I claim is:—

1. Means for controlling the volumetric output and discharge pressure of a fluid machine having an eye, comprising a single intake of rectangular cross section in combination with a cylindrical inlet casing surrounding and concentric with the eye of the machine, half of said cylindrical casing consisting of a stationary part terminating said intake, the other half of the casing being longer than the diameter of the latter and adapted to move along the stationary part and form a throat of variable size in said cylindrical casing for the admission of fluid, and a plate lying in said intake outside the inlet casing and hinged to the movable part of said casing adjacent the throat, and means for moving said movable part of the casing.

2. Means as claimed in claim 1 characterized in that said means for moving the movable part of the inlet casing and the plate hinged thereto comprises a sectorial frame attached to the movable part of the inlet casing and an external handle for operating said frame, the axis of the handle coinciding with the axis of said machine.

THOMAS BOSANKO COLLINS.
